(57) **CLAIM**

The ornamental design for a saddle horn repair grip as shown and described.

DESCRIPTION

FIG. 1 is a perspective view of a saddle horn repair grip of my design.

FIG. 2 is a front end view thereof.

FIG. 3 is a rear end view thereof.

FIG. 4 is a left side view thereof.

FIG. 5 is a right side view thereof.

FIG. 6 is a bottom view thereof.

FIG. 7 is a top view thereof; and,

FIG. 8 is a perspective view showing installation thereof onto a saddle shown in broken lines.

The broken line showing of a saddle in FIG. 8 depicts environmental subject matter and forms no part of the claimed design. The remaining broken lines in FIGS. 2 and 6 depict portions of the saddle horn repair grip that form no part of the claimed design.
